Primary Examiner — Rebekah A Caruso

CLAIM

The ornamental design for a phone stand with earphones organizer, as shown and described.

DESCRIPTION

FIG. 1 is a perspective view of a phone stand with earphones organizer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the phone stand with earphones organizer where the phone stand with earphones organizer is in a configuration of use; and,

FIG. 10 is a perspective view of the phone stand with earphones organizer where the earphones are received in earphones organizer.

The broken lines in the drawings depict portions of the phone stand with earphones organizer that form no part of the claimed design. The broken lines showing earphones in FIG. 10 depict environment that forms no part of the claimed design.

1 Claim, 10 Drawing Sheets
